PORTABLE BATH FOR PHYSIOLOGICAL HEAT TREATMENT

Jack E. Moore and Ann M. Moore, Granite Falls, N.C.
Filed Oct. 4, 1962, Ser. No. 228,466
2 Claims. (Cl. 219—326)

This invention relates to heat treatment baths, and is more particularly concerned with an improved, portable bath for physiological heat treatment.

This application is a continuation-in-part of prior application filed May 22, 1961, Serial Number 111,868 now abandoned.

A standard physiological treatment includes the immersion of an afflicted limb into a bath of liquid paraffin or other heated liquid. For such treatment, it is necessary to have a rather accurate control over the temperature of the liquid; and, it is further necessary to prevent contact of the patient's body with heated surfaces. In addition, it is desirable to allow the patient to be as comfortable as possible, which may include the giving of heat treatments in the patient's home.

In the past, such baths have been provided; however, most such baths are large and cumbersome and difficult to move around, as to a patient's home. Prior art baths have usually included a simple metallic container which is filled with the liquid; and, the container is heated, thereby heating the liquid therein. With such a device, the metallic container is, of course, at a temperature considerably above that of the liquid; hence, if the patient touch the container, quite serious burns could result.

The temperature of the prior art baths has usually been controlled by a thermostat, the sensing element of which is attached to the metallic container; or, in the event that there is a heat exchange liquid, the sensing element has been in that heat exchange liquid. Such an arrangement requires much guessing to determine the actual temperature of the treatment liquid.

The bath of the present invention overcomes the above-stated difficulties by providing a double container, one within the other. The outer container is well insulated to prevent burns. The inner container includes a heat insulating liner which precludes the inadvertent touching of the hot metallic container. A heat exchange liquid is between the inner container and the outer container for gentle heating of the treatment liquid; and, the sensing element for the thermostatic control is located within the inner container and spaced from the metallic wall of the container, thus giving accurate control of the treatment liquid itself. The device is easily portable and includes a convenient support for maximum comfort of the patient using the bath.

It is therefore an object of the present invention to provide an improved heat treatment bath which is easily portable and comfortable to use.

It is another object of the present invention to provide a heat treatment bath which provides accurate temperature control of the treatment liquid.

A further object of the present invention is to provide a heat treatment bath which precludes skin trauma due to contact with a high temperature surface.

Other and further objects, features and advantages of the present invention will become apparent from consideration of the following specification, when taken in conjunction with the accompanying drawings in which:

FIGURE 1 is a perspective view of one preferred embodiment of the present invention, the cover being shown removed therefrom.

FIGURE 2 is a longitudinal cross-sectional view taken substantially along the line 2—2 in FIGURE 1.

FIGURE 3 is a partial horizontal cross-sectional view taken substantially along the line 3—3 in FIGURE 1.

2

FIGURE 4 is a schematic wiring diagram to be used with the embodiment shown.

Referring now particularly to the drawings and to that embodiment of the invention here chosen by way of illustration, the device includes a cabinet 10 supported on casters 11. The sides 12 and 14 are provided with handles, as handle 15 for easy carrying. End 16 of the cabinet has mounted thereon a control box 18 to house the controls to be described hereinafter.

The top 19 of the cabinet 10 has a central opening 20 to give access to the treatment liquid; and, the opening 20 may be covered, when not in use by cover 21. An insulating boss 22 on the cover 21 fits into the opening 20 and prevents undue loss of heat when the bath is not in use.

There is located adjacent the opening 20, a support 25 on which the upper portion of a person's appendage may rest while the lower portion, or outer extremity, is in the bath. The support 25 is a flat, rectangular piece of material (here shown as wood) which is adjustably fastened to the cabinet 10 by straps 26 received on studs 28 and held in place by wing nuts 29. The inner edge of the support 25 is pivotably secured to the top 19 of the cabinet 10 by hooks 29 in eyes 30. The hooks 29 are open so that they can be removed from the eye 30 to remove the support 25 from the cabinet 10; and, the cover 21 is recessed at 32 to receive the eyes 30.

Referring now primarily to FIGURES 2 and 3 of the drawings, it will be seen that there is an outer container 35 insulated from the cabinet 10 by insulating material 36, which may be rock-wool, fiber glass or other material that can withstand the temperatures involved.

The outer container 35 includes an end wall 38 on which are mounted the controls to be described hereinafter. The container 35 is rectangular with the top 39 only partially covering the container. Attached to the inner edges of the top 39 is an inner container 40, also rectangular, and having an open top.

At one end of the bath, there is a filling hole 41 which extends through the cabinet top 19 into the top 39 of the outer container 35. The hole is closed by a loose-fitting plug 42. The plug 42 is sufficiently loose that steam between the outer container and the inner container can escape.

Within the space 44 between the inner container 40 and the outer container 35 there is disposed an electrical heating element 45. The heating element 45 is supported from the end wall 38 of the outer container 35, and, electrical connections are made in the junction box 46. Mounted immediately above the junction box 46 is a thermostatic control unit 48 which includes a pair of thermostats: one bulb-type thermostat 49 is on the end of a tube 50, and the bulb 49 is mounted inside the inner container 40 to indicate the temperature of the treatment liquid; the other is here shown as a bimetallic element 51 disposed within the heat exchange liquid in the space 44, and acts as a safety. It will be noticed from FIGURE 4 that the two thermostats 49 and 51 are in series electrically.

Also in the box 18 is a pair of valves 54 and 55. The valve 54 is attached to a drain pipe 56 to drain the heat exchange liquid from the space 44, while the valve 55 is attached to a pipe 56 to drain the treatment liquid from the inner container 40.

The inner container 40 has a liner 60 which is made of a non-heat conducting material such as wood or plastic. The liner 60 is made of open struts to allow the treatment liquid to contact the heated surfaces of the inner container 40; but, the struts are sufficiently close together to allow a hand or foot to rest on the struts and not contact the heated surfaces of the container 40. The liner 60 has the bottom 61 thereof spaced above the bot-

tom of the container 40 and supported by cross-pieces 62 to decrease the danger of portions of the body contacting the container itself. Small parts of the body, such as the phalanges, can easily slip between the struts of the bottom 61; but, the space gives a measure of safety.

It will thus be seen that the device of the present invention provides an improved bath for physiological heat treatment. In use, a heat exchange liquid such as water is poured into the space 44 through the hole 41; and, the treatment liquid, such as paraffin and oil, is placed in the inner container 40. The circuit is connected to a source of electrical power through conventional means, and the desired temperature is set for the thermostat 49.

The heating element 45 will now heat the water and transmit the heat to the treatment liquid in the container 40 until the thermostat 49 indicates that the temperature is sufficiently high, at which time the heating element is cut off. If the water gets too hot, the thermostat 51 will cut off the heating element.

When the treatment liquid is hot enough, a person can put the afflicted limb into the bath, resting on support 25 for comfort.

Valves 54 and 55 allow the bath to be drained for cleaning and changing the liquids.

The bath of the present invention is simple and easy to use, and is accurately controlled so that it will not inadvertently become too hot. The fact that the temperature sensing bulb is spaced from container walls allows it to indicate the temperature of the liquid itself rather than the walls.

It will of course be understood that the device here presented is by way of illustration only, and is meant to be in no way restrictive; therefore, numerous changes and modifications may be made, and the full use of equivalents resorted to without departing from the spirit or scope of the invention as outlined in the appended claims.

We claim:

1. A bath for physiological heat treatment comprising an outer container, a cabinet, said outer container being received in said cabinet and insulated therefrom, an inner container disposed within said outer container and spaced therefrom, said inner container being constructed

of a heat conducting material, a liner positioned within said inner container formed of open struts of a non-heat conducting material, heating means placed between said outer container and said inner container, and thermostatic control means to control said heating means including a sensing element attached to said liner; a first drain means arranged to drain said outer container including a first drain pipe having a first valve selectively to close said first drain pipe, and a second drain means arranged to drain said inner container including a second drain pipe having a second valve selectively to close said second drain pipe.

2. A bath for physiological heat treatment comprising an outer container, a cabinet, said outer container being received in said cabinet and insulated therefrom, an inner container disposed within said outer container and spaced therefrom, said inner container being constructed of a heat conducting material, a liner positioned within said inner container formed of open struts of a non-heat conducting material, heating means placed between said outer container and said inner container, said heating means being an electric immersion heater, thermostatic control means to control said heating means, said thermostatic control means having two sensing elements connected in series: a first sensing element disposed in said inner container and attached to said liner; a second sensing element disposed between said outer container and said inner container, a top on said cabinet having an opening to give access to said inner container, a support adjustably mounted on said top adjacent said opening, said support being removable from said top, and a cover which is receivable on said cabinet to close said opening in said top.
